(57) **CLAIM**

The ornamental design for a lid for receptacle, as shown and described.

DESCRIPTION

FIG. 1 is a perspective view of a lid for receptacle showing our new design;

FIG. 2 is a right side view thereof;

FIG. 3 is a back view thereof;

FIG. 4 is a left side view thereof;

FIG. 5 is a front view thereof;

FIG. 6 is a top plan view thereof; and,

FIG. 7 is a bottom plan view thereof.

The broken line showing of a receptacle is included for the purpose of illustrating environment and forms no part of the claimed design.
